UNITED STATES PATENT OFFICE.

HENRY J. TAYLOR AND WILLIAM J. TAYLOR, OF PHILADELPHIA, PENNSYLVANIA.

PLUMBER'S TORCH.

SPECIFICATION forming part of Letters Patent No. 542,451, dated July 9, 1895.

Application filed February 19, 1895. Serial No. 538,979. (No model.)

To all whom it may concern:

Be it known that we, HENRY J. TAYLOR and WILLIAM J. TAYLOR, citizens of the United States, both residing in the city and county of Philadelphia, State of Pennsylvania, have invented a new and useful Improvement in Plumbers' Torches, which improvement is fully set forth in the following specification and accompanying drawings.

10 Our invention relates to a plumber's torch; and it consists of a blow-pipe attachment therefor which is readily adjustable and is prevented from being wrenches off, owing to the attachment of said pipe to a sleeve which 15 is movable on the wick-tube of said torch and to a boss on the body of the torch, said boss and sleeve serving as guides for said pipe.

It further consists of novel details of construction, all as will be hereinafter set forth.

20 Figure 1 represents a side elevation of a plumber's torch embodying our invention. Fig. 2 represents a plan view thereof.

Similar letters of reference indicate corresponding parts in the two figures.

25 Referring to the drawings, A designates the body of the torch, and B the wick-tube thereof, the wick being shown at C. The said tube has a sleeve D, whose lower portion D' is made flaring and which slides freely on said tube and has attached to it the air-pipe E, whose top F is closed, said pipe, however, being provided with a vent G near said top, at a point adjacent to said tube. The said air-pipe E has an offset at H, below which it 30 extends down the side of the body A, its lower portion passing freely through the boss J, which serves as a guide, and is provided with a thumb-screw K, which may be tightened against said pipe, whereby the latter and the 35 collar D can be adjusted and held at any required height relative to the wick, said air-pipe having the function of a blow-pipe, as will be hereinafter explained.

40 L designates a piece of rubber tubing, which is attached to the end of said air-pipe and which may or may not be provided with a suitable mouthpiece.

M designates a cap for extinguishing the flame.

The operation is as follows: The wick C having been ignited the air-pipe E is adjusted until the vent G thereof is at the proper place, relatively to the wick, and the screw K is then tightened, it being noticed that the sleeve D, to which the upper portion of the air-pipe is attached, effectually prevents the same from displacement relative to the flame; and if now the ignited wick be brought near the object to be heated or melted and the operator blows through the tubing L and the pipe E a hot flame of the greatest intensity will be concentrated upon the desired point, as is evident, it being noticed that the sleeve and boss serve as guides for the air-pipe and prevent the same from being readily displaced or wrenches from the torch. As the wick burns down the vent G can be adjusted relative thereto with great exactness.

By making the sleeve D flaring at its lower portion D', the same can be readily slipped over the wick without being obstructed by the fibers thereof, as is evident.

Having thus described our invention, what we claim as new, and desire to secure by Letters Patent, is—

1. A plumber's torch consisting of a body, a wick-tube, a sleeve movable on said tube, an air pipe secured to said sleeve, a guiding boss on said body, and a tightening screw on said boss, said pipe being closed at top and provided with a vent in its side, and the parts combined substantially as described.

2. A plumber's torch consisting of a body with a boss on its side, a wick tube, a sleeve movable on said tube, an air pipe secured to said sleeve and having a set-off adapting it to be guided in said boss on said body, and a thumb screw for clamping said pipe in said boss, said pipe having a closed top and an air vent in its side, said parts being combined substantially as described.

HENRY J. TAYLOR.
WILLIAM J. TAYLOR.
